UNITED STATES PATENT OFFICE.

SAMUEL B. GOFF, OF EAST CREEK, NEW JERSEY.

WINDMILL.

SPECIFICATION forming part of Letters Patent No. 223,725, dated January 20, 1880.

Application filed November 7, 1879.

To all whom it may concern:

Be it known that I, SAMUEL B. GOFF, a citizen of the United States, residing at East Creek, in the county of Cape May and State 5 of New Jersey, have invented a new and useful Improvement in Windmills, of which the following is a specification.

My invention relates to that class of windmills in which the wheel revolves in a vertical 10 plane; and the nature of the invention mainly consists in the combination, by means of a cord, rod, or equivalent device, of pairs of sails, which are pivoted at each end and in the middle horizontally, and have a weighted 15 edge, whereby each sail throughout the whole series is so controlled as to be brought to and kept in a vertical position, or nearly so, and thus to receive squarely on its broad side next to the wind the whole force thereof while passing 20 through the upper part of the circuit above the axis of the wheel. The lower half of the circuit is protected by means of a screen in the usual manner.

The invention further consists in a novel 25 mode of adjusting the rudder by means of a polygonal hub on the upper end of the vertical central shaft of a revolving frame which supports the wind-wheel, the lower edge of the rudder having a corresponding recess, which 30 engages with said hub.

When an adjustment of the rudder is to be made it is lifted out of its connection with said hub by means of a cord, one end of which passes over a pulley connected with the stationary frame of the mill, the other end being extended to a convenient place for its manipulation.

In the accompanying drawings, which make a part of this specification, Figure 1 is a side 40 elevation of the wind-wheel, the revolving frame B, and stationary frame A. Fig. 2, Sheet No. 2, is an end elevation of the same, a portion of the frame A being broken away to exhibit the wheel clearly. Fig. 3 is a side 45 elevation, on an enlarged scale, of the upper end of the central shaft, C, the pulley L, and a portion of the rudder E. Fig. 4 is a horizontal section at the broken line xx of Fig. 3.

Like letters of reference in all the figures 50 indicate the same parts.

A represents the standing frame of my im-

proved mill; B, a revolving frame connected therewith by means of the vertical revolving shaft C, the lower end of which connects with the step b in the sill of said frame A, and is 55 supported near its upper end in a bearing in the upper part of the frame. D D are the sides of the wind-wheel, which have stud or wing journals $c c$, that have bearings in the frame B, whereby the wheel is adapted to turn 60 in a vertical plane.

The frame B, by means of the connection of its vertical shaft C with the frame A, is shifted by the action of the rudder E in the automatic adjustment of the wind-wheel. 65

There are any desirable number of pairs of sails G connected with the side pieces, D D, of the wheel by means of pivots d in the ends of the sails.

There are cords or rods H, which are connected at their ends with the edge e of pairs of sails G at opposite sides of the wheel, as clearly seen in Fig. 1. These connected edges are weighted by means of metallic strips e' , for the purpose of bringing the sails into a 70 vertical position and retaining them in that position while they are passing through the upper part of their circuit above the annular screen I, and also to stiffen the edge. The position of the sails causes their weighted edge 75 to be in front of the line of motion of the wheel while the latter passes through the lower half of the circuit. To reverse their position is the office of the cords H, which is done by the tendency of each sail to keep in a vertical position, exerting a pulling-force as it comes to the point x before passing behind the screen I, by means of the cord H upon the opposite sail at the point x' , and thus to turn it over on its pivots before the latter comes above the screen 85 to receive the force of the wind on its broad side.

E is the vane on the upper end of the vertical shaft C for regulating the position of the wheel to bring the sails G square with the 90 wind or on an angle therewith, as may be desired.

For a convenient, simple, and quick adjustment of the vane I connect its socket f at its lower edge with the hub g of the shaft, (seen 100 in Figs. 3 and 4,) the nut having any desirable number of sides, so as to vary the position

or angle of the vane by withdrawing the vane upward to clear the socket *f* from the hub *g* and giving the vane a partial turn around on the shaft *C* to make the alterations, and then again connecting the socket with the hub.

5 The withdrawal of the vane is effected by means of the cord *K* and pulley *L*, one end of the cord being attached to the vane, as seen in Fig. 1, and the other end being at any desirable position for manipulating it. The pulley *L* is connected with the yoke *M*, which has a permanent connection with the frame *A*; or the pulley may be held by any other convenient device.

15 I claim as my invention—

1. In a wind-wheel running in a vertical plane, the combination of a series of pivoted sails having metallic weight-strips *e* at one edge, substantially as set forth.

2. The combination of the cords or rods *H* 20 with pairs of sails *G*, the ends of the cords being connected with weighted edges of the sails, substantially as and for the purpose set forth.

3. The combination of the vane *E* with the 25 shaft *C*, connected thereto by means of the polygonal hub *g* and corresponding socket *f*, for the adjustment of the vane in its position to the wind-wheel, substantially as and for the purpose set forth.

4. The combination of the cord and pulley *L* with the vane *E* and yoke *M*, substantially as and for the purpose set forth.

30

SAMUEL B. GOFF.
